D. R. INGRAM,
HYDRAULIC OIL ELEVATOR,
APPLICATION FILED OCT. 10, 1919.

1,355,606.

Patented Oct. 12, 1920.

UNITED STATES PATENT OFFICE.

DAVID R. INGRAM, OF KANSAS CITY, MISSOURI.

HYDRAULIC OIL-ELEVATOR.

1,355,606.

Specification of Letters Patent. Patented Oct. 12, 1920.

Application filed October 10, 1919. Serial No. 329,670.

To all whom it may concern:

Be it known that I, DAVID R. INGRAM, a citizen of the United States, residing at Kansas City, in the county of Jackson and 5 State of Missouri, have invented certain new and useful Improvements in Hydraulic Oil-Elevators; and I do declare the following to be a full, clear, and exact description of the invention, such as will enable others 10 skilled in the art to which it appertains to make and use the same, reference being had to the accompanying drawings, and to the letters and figures of reference marked thereon, which form a part of this specification. 15

This invention relates to a method of and apparatus for elevating oil in wells and has for its object the utilization of hydrostatic pressure for effecting displacement of the 20 oil.

The invention contemplates the use of suitable apparatus for supplying a flow of water to the well and directing the flow of oil and water to the surface; a packer being 25 preferably introduced into the well above the oil level and, where natural or incidental water is present, one below the oil sand strata so as to confine the oil in a localized zone where it may be efficiently 30 acted upon by the designedly introduced water to raise it so that the oil may be easily recovered from the well.

In the drawings,

Figure I is a perspective view of the general organization of a hydraulic oil elevator constructed in accordance with my invention, parts being broken away to better illustrate the interior of certain of the elements. 35

Fig. II is a side elevational view of the 40 upper packer and fragments of the tubes, and

Fig. III is a vertical, longitudinal, sectional view through a portion of the well casing, showing the upper packer in section 45 and part of the lower packer in section.

Referring now to the drawings by numerals of reference.

The well, of conventional construction, is indicated by the casing 1, there being an oil 50 sand strata 2, adjacent thereto and a water sand strata 3 below the same. A packer 5 may be introduced at about the top of the oil level and, where natural or incidental water is present, I prefer to introduce a 55 stopper or packer 4 at about or below the

bottom of the oil strata, the two packers forming a chamber 6 within which oil, passing through the screened section 7 in the casing, may collect to be acted upon by the hydrostatic pressure, as presently described. 60 Leading from a water reservoir or tank 8 at the top of the well, is a pipe or conduit 9, projecting through the packer 5 and provided with a turned-up end 10, discharging into the chamber 6 formed by the packers 65 4 and 5. A pipe 11 also projects through the packer 5 and has its inlet end 12 preferably adjacent to the outlet end 10 of the pipe 9; the outlet end of the pipe 11 is indicated at 13 to discharge into the reservoir 70 or tank 8.

The tank is provided with a float-actuated valve 14 adapted to close the inlet 15 of the pipe 9 when the level in the reservoir 8 has risen to a predetermined point. 75

When the parts are assembled as shown, the water cock 16 may be opened to permit water to flow through pipe 9, discharging at 10 into the chamber 8, displacing the oil accumulating in said chamber and forcing it up through pipe 11 into the reservoir 8 by hydrostatic pressure. If there is no free water present, the packer 4 may be dispensed with although it is generally good practice to employ a packer similar to that 85 indicated by the numeral 4.

When a determined quantity of oil has been discharged into the reservoir 8, it may be skimmed or otherwise removed from the water therein and treated in the usual way. 90

From the foregoing, it will be apparent that the device may be readily applied to existing types of wells and that the maintenance cost will be practically *nil*, thereby enabling the recovery of oil from the well 95 at a minimized cost and dispensing with the necessity for employing expensive machinery or kindred apparatuses for accomplishing the same result.

What I claim and desire to secure by 100 Letters-Patent is:

1. In a hydraulic oil elevator, a packer, a pipe projecting through the packer and having its inlet above the packer and its outlet below the packer, a pipe having its 105 inlet below the packer and its outlet above the packer, a water reservoir communicating with the first named pipe, the second mentioned pipe having a discharge over the water level in the reservoir and a float valve 110

for closing the inlet in the first named pipe when the level in the reservoir reaches a determined level.

2. In a hydraulic oil elevator, a packer, 5 a pipe projecting through the packer, a water reservoir above the packer and communicating with the inlet end of the pipe, a pipe extending through the packer and having its inlet below the packer and its 10 outlet discharging into the reservoir, and a float-actuated valve in the reservoir for controlling the effective port area of the inlet to the first named pipe.

3. In a hydraulic oil elevator, a well casing 15 having a perforate portion near its lower end, a packer for the lower end of the casing, a packer above the perforate portion of the casing, a pipe projecting through the upper packer and having its inlet above 20 the packer and its outlet below the packer,

a pipe having its inlet below the upper packer and its outlet above the upper packer, and a water reservoir communicating with the first named pipe.

4. In a hydraulic oil elevator, an oil well 25 casing having a perforate lower end, a packer above the perforate lower end, a pipe projecting through the packer and having its inlet above the packer and its outlet below the packer, a second pipe projecting 30 through the packer and having its inlet below the packer and its outlet above the packer, a water reservoir communicating with the inlet of the first named pipe, and means in the reservoir for controlling the 35 effective port area of the inlet to the first named pipe in response to variations of fluid level within the reservoir.

In testimony whereof I affix my signature
DAVID R. INGRAM,
